UNITED STATES PATENT OFFICE.

HENRY SAMUEL SPILLER WATKIN, OF THE WILDERNESS, CANTWELL ROAD,
WOOLWICH, COUNTY OF KENT, ENGLAND.

ANEROID BAROMETER.

SPECIFICATION forming part of Letters Patent No. 394,668, dated December 18, 1888.

Application filed February 27, 1888. Serial No. 265,389. (No model.) Patented in England November 13, 1886, No. 14,730.

To all whom it may concern:

Be it known that I, HENRY SAMUEL SPILLER WATKIN, of The Wilderness, Cantwell Road, Woolwich, in the county of Kent, England, major royal artillery, have invented certain new and useful Improvements in Aneroid Barometers, (for which I have obtained Letters Patent of the United Kingdom of Great Britain and Ireland, dated November 13, 1886, and numbered 14,730,) of which the following is a specification.

The invention relates to that class of aneroid barometers which are provided with a large open scale, or a scale extended beyond the ordinary scale into two or more circles or convolutions, so as to increase the distance between the graduations or reading-points, and in combination with which the index-hand or pointer is required to make two or more complete revolutions.

In such class of instrument the volute spring ordinarily employed to control the motion of the hand or pointer spindle is found to buckle, and therefore to act irregularly on the said spindle. The first part of the invention consists of means for remedying this defect, and the second part relates to improvements in the indicating mechanism of such class of barometers.

In the accompanying drawings I have represented various modes in which my invention may be carried into effect.

In all the figures like parts are indicated by similar letters of reference.

Figure 1 is an elevation, partly in section on the line 1 1, Fig. 2, showing the principal working parts of the instrument and omitting the casing and dial. Fig. 2 is a front view of the same parts, partly in section on the line 2 2, Fig. 1. Fig. 2^a is an elevation of the indicator portion of the mechanism shown in Fig. 2. Fig. 3 is an axial section of the entire instrument, on a smaller scale, on the line 3 3, Fig. 4. Fig. 4 is a face view thereof. Fig. 5 is an elevation of the parts shown in Fig. 1, but representing the substitution of a cylindrical coiled spring for the helical hair-spring shown in Figs. 1 and 2. Fig. 6 is a partial face view showing a modification in the dial. Fig. 6^a is an elevation of the indicator portion of the mechanism shown in Fig. 6. Fig.

7 is an elevation illustrating another modification in the controlling-spring. Fig. 8 is a front view of the same parts. Fig. 9 is an axial sectional elevation showing another 55 modification in the controlling-spring. Fig. 10 is a partial face view of the same parts. Fig. 11 is an axial sectional elevation illustrating a modification in the device to indicate the scale from which the reading is to be 60 taken. Fig. 12 is a partial face view of the same parts. Fig. 13 illustrates a modification in which the dial rotates beneath a fixed indicator.

a represents the case of the instrument; *b*, 65 the vacuum-chamber; *c*, the counteracting-spring; *d*, the operating-lever attached to and operated by the spring *c*; *e*, a link connecting the lever *d* to an adjustable arm, *f'*, fixed on the rocking bar *f*; and *f²*, an arm or lever, 70 also fixed to the rocking bar *f*, and which has its upper end connected by a chain, *g*, to a worm or screw, *h'*, formed or fixed on the spindle *h*, carrying the reading hand or pointer *i*.

The spindle *h* is mounted in bearings carried by the bracket *j*.

The parts above described form no part of my present invention.

In such class of instrument it is usual to 80 employ a volute spring, *l*, sufficient to control the motion of the hand or pointer spindle *h* to the extent of a single revolution; but such spring, when employed in combination with a hand or pointer which is required to make 85 two or more complete revolutions, is found to buckle, and therefore to act irregularly on the spindle *h*. In order to remedy this defect, I, according to one arrangement, as shown at Figs. 1, 2, 3, and 11, inclose the said volute 90 spring, *l*, in a suitable box or case, *m*, which is so proportioned as to permit of the full action of the spring *l*, and is yet so shallow as to prevent the buckling thereof when it has performed more than a complete turn, thus enabling the controlling-spring to accomplish 95 the additional work required of it in connection with the spindle of an open-scale aneroid barometer.

In another modification, as represented at 100 Figs. 5 and 6, I substitute for the ordinary volute spring, *l*, a cylindrical coiled spring, *l'*,

surrounding the index-hand or pointer spindle h , and of sufficient length to enable it to make the required number of revolutions and yet to act efficiently on the spindle h .

- 5 According to another arrangement, as represented at Figs. 7 and 8, I fix one end of a cylindrical coiled spring, l^{**} , to a fixed stud, n , while the other end is connected to a thread or ligature, l' , passed several times round a 10 spiral groove or screw-thread, h^2 , formed on the spindle h , and such thread or ligature l' is fixed to the spindle h beyond such spiral groove or screw-thread h^2 , which latter is formed in the opposite direction to that of 15 the screw-thread or worm h' , around which the chain or other connection g , actuating the spindle h in one direction, is coiled. The spring l^{**} may occupy the position shown by either the full lines or the dotted lines in 20 Fig. 8.

In still another modification, as represented at Figs. 9 and 10, I employ a volute spring, l , of the ordinary form; but I fix it to and around a separate spindle, o , which has a 25 toothed wheel, o'' , fixed thereon, which works into a toothed pinion, h^3 , fixed on the hand or pointer spindle h , whereby any required number of revolutions may be given to the latter and a smaller number to the spring-spindle 30 o , thereby securing the correct action of the spring l upon the hand or pointer spindle h .

I would here remark that the improvements above described are equally applicable to aneroid barometers of the character described 35 in the specification of Letters Patent granted to me June 14, 1887, No. 364,692.

In carrying out the second part of my invention I in some cases employ a dial, k , with two or more concentric circles of scales engraved thereon, as represented at Figs. 2, 4, 40 6, 10, and 12, and in combination therewith I employ a hand or pointer, i , sufficiently long to extend across all of such concentric circles, and according to one arrangement, as 45 shown at Fig. 4, I form such hand i with as many fingers or pointers i' as there are circles of scales, each of such pointers i' pointing to a separate circle; and in order to indicate which circle of scales should be looked 50 at I employ, according to the arrangement shown at Fig. 2, an indicator, p , connected to or operated by the rocking bar f and chain g , giving motion to the hand or pointer spindle h in such manner as to cause such indicator 55 p to point to the circle of divisions and figures to be looked at, the diameter or trace of the circle being made to correspond to the movement of the pointer p for each complete turn of the index-finger i ; or, according to the 60 arrangement represented at Fig. 6, I cause such indicator hand or pointer p to point to one or other of a series of figures, "1 2 3," engraved on the dial-plate k , to indicate which scale or circle of divisions and figures is to be 65 looked at; or I form such indicator p , as represented at Figs. 3, 4, 9, and 10, with a series of

figures engraved on a plate, p' , carried by a link, p^2 , one end of which is connected to the upper end of the arm f^2 and the other to the chain g . Thus either of the figures will be 70 exhibited through an aperture, k' , in the dial k , according to which circle of divisions and figures is to be observed; or the movement of the rocking bar f and chain g may, as represented at Figs. 11 and 12, cause the revolution 75 of an indicator or finger, p , on a small circle, k^2 , on the dial-plate k . This circle k^2 is engraved with figures denoting which circle of graduations is to be read under the index-needle i . In carrying this arrangement 80 into effect the indicator p is mounted on an axis, p^3 , which has fixed thereon a screw-thread, p^4 , around which the chain g passes in its way from the arm f^2 to the spindle h .

In the various arrangements represented at 85 Figs. 2, 4, 6, 10, and 12 the dial-plate k has arrows k^3 engraved thereon between the several circles of scales, in order to indicate the points where the reading of one circle ends and another begins. The hand or pointer i 90 may, if desired, extend only to the inner circular scale, in which case I employ a movable pointer, q , connected to a movable ring, r , on the case, and extending across all the scales and nearly meeting the hand or pointer i , so that 95 any scale can be read off by placing the said movable pointer in line with the hand or pointer i , as shown by the dotted lines in Fig. 4.

The breaks in the concentric scales or circles represented in Figs. 2, 4, 6, 10, and 12 readily show the points at which the reading is to be transferred from one scale to the next, and the figures arranged in either of the various modes described indicate at once to the observer which scale is to be read to show the 105 correct indication.

Having thus described my invention, the following is what I claim as new therein and desire to secure by Letters Patent:

1. An aneroid barometer having a large 110 open scale and a hand or pointer adapted to make more than one revolution, and a controlling-spring guided or controlled to prevent buckling, substantially as herein described.

2. An aneroid barometer having a hand or 115 pointer adapted to make more than one revolution, and a dial with two or more concentric scales on which the indications of the hand or pointer are successively read, the graduations on the outer scales forming a continuation 120 of the inner scale, substantially as set forth.

3. An aneroid barometer having a reading hand or pointer adapted to make more than one revolution, several concentric scales on 125 which the indications are to be successively read, and a hand or pointer for indicating which scale is to be observed, substantially as described.

4. An aneroid barometer constructed with 130 a large open scale, a spindle having a hand or pointer adapted to make more than one

- revolution, a volute spring, and a box or case controlling the spring, substantially as described.
5. An aneroid barometer constructed with a large open scale and a spindle having a hand or pointer adapted to make more than one revolution, provided with two or more fingers, *i*, for different parts of the scale, substantially as described.
10. 6. An aneroid barometer constructed with an open scale, a spindle having a hand or pointer adapted to make more than one revolution, a rock-bar having an arm, a chain connecting the arm to the spindle, and an indicator operated by the spindle and arm, substantially as described.
15. 7. An aneroid barometer constructed with an open scale, a spindle having a hand or pointer adapted to make more than one revolution, a rock-bar having an arm, a chain connecting the arm to the spindle, a slotted dial, and an indicator, *p*, working in the slot of the dial, substantially as described.

HENRY SAMUEL SPILLER WATKIN.
